J. D. ROSS

SPRINKLER NOZZLE

Filed April 12, 1921

Fig. 3.

Inventor
John D. Ross

By
Edward L. House
Atty.

UNITED STATES PATENT OFFICE.

JOHN D. ROSS, OF PASADENA, CALIFORNIA.

SPRINKLER NOZZLE.

Application filed April 12, 1921. Serial No. 460,731.

To all whom it may concern:

Be it known that I, JOHN D. ROSS, a citizen of the United States, residing at Pasadena, in the county of Los Angeles, State of California, have invented new and useful Improvements in Sprinkler Nozzles, of which the following is a specification.

My invention relates to a sprinkler nozzle of the type illustrated and described in my 10 U. S. Letters Patent No. 752,803, of February 23, 1904, entitled Nozzle for sprinklers, and pertains to an improvement thereon.

In the construction illustrated and described in patent above referred to, the 15 streams of water issued from a centrally disposed group of perforations in the sprinkler plate or head in an uneven manner, due mainly to an uneven pressure within the sprinkler chamber, the streams at the sprinkler ends issuing with greater force therefrom than from the centrally disposed group of perforations.

By means of my improved device the 20 streams of water will issue from the various perforations in an even and uniform manner, the pressure being equally distributed in the chamber behind the perforated plate or head.

The above object is accomplished by means 25 of the device disclosed herein and illustrated in the accompanying drawings, in which:

Fig. 1 is a side elevation of my improved sprinkler nozzle.

Fig. 2 is a central longitudinal section 30 through the same.

Fig. 3 is a cross section of the nozzle taken on line 3—3 of Fig. 1.

Referring more specifically to the drawings, 5 designates a sprinkler nozzle, preferably consisting of an elongated water pressure chamber 6, provided with a bottom wall 7, side walls 8, a perforated top wall 9 of segmental form, end walls 10 and a threaded water inlet hose coupling 11 secured to the bottom wall and located midway of end walls 10. The whole construction is preferably formed of a non-corrodible metal such as sheet brass and formed by means of dies.

The sprinkler perforations are formed in 50 the segmental wall 9 at right angles thereto, so that the streams of water issuing therefrom will be directed in a "fan shape." All of the above construction is substantially the same as illustrated and described in my patent heretofore referred to.

Mounted directly above the water inlet 11

of chamber 6 and approximately midway between bottom wall 7 and top wall 9 is a horizontally disposed water deflecting plate 14, its side edges seating within depressions 15 60 formed in the side walls 8 of the sprinkler water pressure chamber.

By means of the above construction the stream of water passing into chamber 6 will be evenly distributed so that the streams will 65 issue from all the perforations in the wall 9 in a uniform manner instead of the perforated segmental top wall 9, thereby equalizing the water pressure evenly throughout the area of chamber 6, the streams issuing 70 from all the perforations in a uniform manner.

What I claim is:

1. In a sprinkler nozzle construction, a 75 sprinkler head forming a water pressure chamber, one wall of said chamber being of elongated segmental form with parallel side edges, said wall being provided with a plurality of water discharge outlets or perforations, the oppositely disposed wall being 80 provided with a water inlet opening, a threaded hose connection secured in said inlet, and a deflecting plate rigidly mounted above the water inlet and disposed transversely thereof. 85

2. A sprinkler nozzle construction comprising a casing having a water inlet leading thereto and a plurality of water discharge outlets, said discharge outlets occupying an area of elongated curved formation, and a deflector plate arranged in the path of the water from the inlet to the central discharge outlets. 90

3. A sprinkler nozzle construction, comprising a metallic casing consisting of side, 95 end, bottom and top walls forming an elongated pressure chamber, the top wall of said casing being provided with a plurality of perforations or water outlets disposed throughout its entire area, said casing having a water inlet pipe leading thereto, said water inlet pipe being disposed substantially midway of the ends of said casing, and a deflecting plate rigidly mounted in 100 said chamber directly above the water inlet leading thereto, whereby the water will issue through all the perforations in the top wall with equal force. 105

In witness that I claim the foregoing I have hereunto subscribed my name this 29th 110 day of March, 1921.

JOHN D. ROSS.
